CARBURETOR

Edgar R. Schneider, St. Louis, Mo., assignor of
one-tenth to said Schneider, as trustee for Olaf
H. Anderson, Salt Lake City, Utah

Continuation of application Serial No. 487,701,
May 20, 1943. This application January 12,
1944, Serial No. 518,204

6 Claims. (Cl. 261—41)

1

This invention relates to improvements in compensating carburetors. More particularly, this invention relates to improvements in carburetors wherein the volume of air and fuel varies to compensate for variations in the load on the engine connected to the carburetor.

It is therefore an object of the present invention to provide an improved carburetor wherein the volume of air and fuel is variable.

This invention is a continuation of the invention disclosed in my co-pending application Serial No. 487,701 entitled "Multiple Venturi carburetor" which was filed May 20, 1943.

The running system of a carburetor usually consists of a Venturi tube in which a jet is positioned. This jet is positioned adjacent the section of the Venturi tube that has the smallest internal diameter, and it will emit fuel when the velocity of the air passing through the venturi reaches a predetermined value. Since the velocity of air passing through the venturi depends on the internal diameter of the Venturi tube, as well as the volume of air required by the engine, the velocity of air passing through a venturi can, for any given volume of air, be increased by decreasing the diameter of the venturi. Such an increase in the velocity of air, for any given volume of air required by the engine, would cause the running system to begin to operate at much lower engine speeds than is now possible. For example, modern running systems may not begin to operate until the engine attains a speed corresponding to 20 or 25 miles per hour in high gear. By reducing the diameter of the venturi, it is possible to have that running system begin to operate at a speed corresponding to 9 or 10 miles per hour in high gear. Having the running system come into operation at such low engine speeds is highly desirable since running systems invariably are much more efficient than are idling systems. Such an arrangement, therefore, permits the engine to run at a higher efficiency for a greater percentage of the running time, and thereby achieves a greater overall efficiency. It is therefore an object of the present invention to provide a carburetor wherein the running system begins to operate at low engine speeds.

The needs of an engine are quite variable and they must be fully met or the engine will not give its maximum efficiency. The best and most accurate index of the needs of an engine are the pressures at the intake manifold of the engine. The present invention makes use of these pressures to vary the volume of air and fuel provided

2

by the carburetor and thereby achieves the proper amount of air and fuel for each load condition. It is therefore an object of the present invention to provide a carburetor which provides the proper amount of fuel and air for any given load or speed, and varies the volume of fuel and air commensurate with the pressures at the intake manifold of the engine.

The present invention is enabled to have its running system begin to operate at low speeds, to change the volume of fuel and air commensurate with the pressures at the intake of the engine and to provide for adequate air volume at all speeds by using at least two Venturi tubes in addition to the idling system. One of these Venturi tubes is closable only by a master throttle valve, while the other is closable by the master throttle valve and a secondary throttle valve. The venturi that is closable only by the master throttle valve will provide a fuel and air mixture whenever the running system is operating, while the other venturi will provide a fuel and air mixture whenever the running system is operating and the secondary throttle valve is open. The volumes of mixture provided by the two Venturi tubes will preferably be such that they can unite to give a combined volume of fuel and air that will provide the necessary power for acceleration periods. In this way, the invention can provide one range of fuel-air volumes for constant velocity and even-load conditions and can supply another range of fuel-air volumes whenever a heavy load is placed on the engine or the speed is to be increased. It is therefore an object of the present invention to provide an improved carburetor having a venturi that is closable only by a master throttle valve and a second venturi that is closable by a master throttle valve and a secondary throttle.

The use of a small, normally open primary venturi that is closable by a master throttle valve is further desirable because it affords a high velocity of air through the open venturi. This high velocity not only causes the running system to begin to operate at low engine speeds, but it also provides better atomization of the fuel. Such high atomization is quite useful because it increases the economy and efficiency of the engine. It is therefore an object of the present invention to provide a carburetor wherein the fuel is highly atomized.

These and many other objects I accomplish with the device illustrated in the accompanying drawings in which similar numerals and letters of reference indicate like parts throughout the several

views. In the drawing and accompanying description, a preferred form of the invention is shown and described but it is to be understood that the drawing and accompanying description do not limit the invention and the invention is defined by the appended claims.

In the drawings in which I have shown my invention,

Figure 1 is a vertical section of the carburetor; and that section is taken along the center line of the carburetor, but the section of the partition between the two mixture passages is taken along a line spaced behind the center line.

Figure 2 is a side elevational view of the carburetor taken ninety degrees from that shown in Figure 1, and it shows the positioning of the vacuum control diaphragm.

Figure 3 is a section on line 3-3 of Figure 1.

Figure 4 is a vertical section through the carburetor of Figure 2.

In the drawings I have shown the carburetor as made of a Venturi casing A, having the lower end 5 provided with a securing flange by which it may be secured to the intake manifold of the engine. The Venturi casing A starts as a cylindrical chamber 6 in which a master throttle valve 7 is pivotally mounted and an idling jet 30 is provided. This jet can best be seen in Fig. 4 where it is shown in proximity to the master throttle valve 7. Feeding this jet is a duct 40 that supplies gasoline from the source of fuel. Adjacent jet 30 is the idle air screw 42 that is standard equipment on present-day carburetors. The chamber 6 then merges into an outwardly flared chamber 8 which then merges into dual Venturi tubes formed by a dividing partition 9 that divides the chamber into air ducts a and b. A dual Venturi casting 10 is set in the top end of the casing A, which casting carries depending spaced Venturi tubes 11 and 12 that are adapted to be set into the dual Venturi casting 10 of the casing A to form the perfectly bored and fabricated Venturi tubes for drawing the fuel from the jets into the air stream. Venturi tube 11 is larger in diameter than is tube 12, and the sum of the areas of the tubes 11 and 12 is equal to or greater than the area of the single or multiple venturis used in present-day carburetors. Such an arrangement is desirable to provide an adequate flow of air and fuel to the engine at all positions of the master throttle valve.

Each of these Venturi tubes are identical in form and they are divided by a central partition. Within the Venturi tubes there are smaller Venturi tubes 13 and 14 spaced axially therein and supported from a bracket on one side for holding it in position in the air stream and it is into these two smaller Venturi tubes that the fuel jets 15 and 16 are set. The fuel jets 15 and 16 are connected to a suitable source of fuel, not shown, that supplies the fuel for the carburetor. Interposed between the jets 15 and 16 are metering devices, not shown, that determine the rate of fuel flow to the jets and thereby determine the rate of fuel flow to the jets, which of course determines the air-fuel ratio of each of the venturis. These metering devices are so arranged that the combined mixture of the two venturis approximates the mixtures common in present-day carburetors. Volume of the mixture afforded by the venturi 14 is adequate to operate the engine at constant velocity under light loads, and will give exceptionally economical performance. During periods of acceleration, the ven-

turi 13 will open to increase the volume of the combined mixture to the desired degree.

Above these Venturi tubes and their housing, there is a constructed air inlet connection 19 which is provided with the usual butterfly choke valve and onto the top end of the connection the air cleaner is usually mounted. Within the larger of the air ducts a I provide a butterfly control valve 20 mounted on the rod 21 which extends through the outside wall to a control plate 22. The inner end of the rod 21 is mounted in the partition 9 to give it rigid support. The outer end of the rod 21 is also provided with an adjustable stop to insure against suction locking of the butterfly in high vacuum conditions. A crank pin 23 extends from the plate 22 and a link 24 is carried on the pin 23 with the free end thereof attached to and controlled by a flexible diaphragm 32 carried in the diaphragm casing 25. A spring 34 biases the valve 20 to open position, but the valve will move to closed position during conditions of sub-atmospheric pressure in the cylindrical chamber 6. The spring 34 is positioned in the horizontally disposed cylinder 33 extending to the left of the diaphragm casing 25 in Fig. 2 of the drawing. One end of the spring 34 bears against the flexible diaphragm and the other bears against the end of the adjusting screw 36 threaded in the screw-retaining cylinder. Adjustment of this screw is useful in determining the pressures to which the valve 20 will be responsive. A line 26 from one side of the cylindrical chamber 6 below the throttle valve leads to the closed side of the vacuum control so that the suction or vacuum of the motor is utilized to control the butterfly valve 20 and the valve is therefore controlled commensurate with the pressure at the intake manifold of the engine.

When the engine is at rest, the master throttle valve 7 will be closed, and the throttle valve 20 will be open. The master throttle valve 7 is the usual type of pedal operated throttle valve now used in most present-day carburetors and is spring biased toward closed position. The throttle valve 20 on the other hand is biased to open position by the spring 34 that is positioned and held in the horizontally disposed cylinder 33 shown in Fig. 2.

When the engine is started, the master throttle valve 7 may still remain in closed position, but the throttle valve 20 will be moved to closed position. This closing of the valve 20 is effected by the flexing of the pressure responsive diaphragm 32, which flexing will cause a movement of link 24 and a consequent rotation of plate 22 and valve 20. The flexing of the diaphragm 32 is the result of a difference between the pressures on the opposed surfaces of the diaphragm. Atmospheric pressure will be exerted on one side of the diaphragm and a sub-atmospheric pressure will be exerted on one side of the diaphragm. The sub-atmospheric pressure on the one side of the diaphragm is obtained by placing that one side of the diaphragm in communication with the atmosphere in the portion of cylindrical chamber 6 which is adjacent the intake manifold of the engine. This is done by use of the conduit 26.

When the engine is idling, the pressure in the intake manifold will be considerably below atmospheric pressure and will easily overcome the force exerted by the spring and will thereby close the valve 20. While the valve 20 is closed, the venturi 13 will be closed and the venturi

14 will have to provide the air necessary to draw fuel from the idling jet 30 of the engine.

As soon as the master throttle valve 7 is opened a little, the pressure in the intake manifold will increase. This increase in pressure will decrease the pressure differential on the opposed surfaces of the diaphragm 32 and will reduce the force exerted against the valve spring 34. This reduction in force on the spring will permit the valve 20 to open up somewhat. The valve 20 will remain open until the pressure in the intake manifold again decreases, as it will when the engine reaches a near-constant velocity. The valve 20 will again open if the throttle valve 7 is opened further, because such further opening will again increase the pressures in the intake manifold.

This arrangement is highly desirable because it opens the valve 20 and thereby increases the volume of the mixture whenever the master throttle valve 7 is opened further. Such increasing of the volume of the mixture is highly desirable because the further opening of the master-throttle 7 usually occurs when the engine is to accelerate. From this it is apparent that the engine will run on the volume of mixture from venturi 14 whenever the engine is running at constant or near-constant velocity, and will be given an additional volume of mixture whenever it needs it, as it will during periods of increased load and acceleration.

In the event that it is deemed advisable to cast the casing A with the Venturi tubes as integral parts thereof rather than as inserts as shown in the drawings, applicant feels that this should be considered merely a structural detail and not of patentable moment. It will also be possible to cast a cylindrical body in the casing A and use a piston therein rather than using the plate type diaphragm shown in the other views of the drawings. Mention is being made of these variations and possible changes to show that such modifications have been made and are possible but are considered to be within the spirit of this invention and the scope of the appended claims.

What I claim is:

1. In a carburetor of the character described, a casing providing a single fuel mixture outlet at one end and a single air inlet at the opposite end, said mixture outlet being adapted for connection to an intake passage of an internal combustion engine, a manually operable throttle valve in said outlet, a primary mixture passage in the casing intermediate said inlet and said outlet, an auxiliary mixture passage in the casing in parallel with the first said mixture passage, a Venturi tube in each of said passages, a fuel jet operatively associated with each of said Venturi tubes, a control valve in the downstream end of said auxiliary mixture passage, means normally tending to open said control valve, and a movable wall subjected on one side thereof to the pressure downstream of said manually operable throttle valve to close said control valve by predetermined engine suction.

2. In a carburetor of the character described, a casing providing a single fuel mixture outlet at one end and a single air inlet at the opposite end, said mixture outlet end being adapted for connection to an intake passage of an internal combustion engine, a manually operable throttle valve in said outlet, generally parallel primary and auxiliary mixture passages in said casing intermediate said inlet and outlet, a Venturi tube in each of said passages, a fuel jet operatively associated with each of said Venturi tubes, a

control valve in the discharge end of said auxiliary mixture passage, means normally tending to open said control valve, and a pneumatic motor communicating with said mixture outlet by a conduit that opens directly into said mixture outlet downstream of said manually operable throttle valve to close said control valve by predetermined engine suction.

3. In a carburetor of the character described, 10 a casing providing a fuel mixture outlet and an air inlet, said mixture outlet being adapted for connection to an intake passage of an internal combustion engine, a manually operable throttle valve in said mixture outlet, a primary and an auxiliary mixture passage in parallel relation in said casing, said mixture passages communicating said air inlet with said mixture outlet, a Venturi tube in each of said mixture passages, a control valve in said auxiliary mixture passage, a spring-loaded pressure-responsive diaphragm 20 operatively connected to said control valve, and conduit means between one side of said diaphragm and a point in said mixture outlet downstream of said manually operable throttle valve, said spring-loaded pressure-responsive diaphragm biasing said control valve to open position and being operable by predetermined engine suction to close said control valve.

4. In a carburetor of the character described, 30 a casing providing a fuel mixture outlet and an air inlet, said outlet being adapted for connection to an intake passage of an internal combustion engine, a manually operable throttle valve in said mixture outlet, primary and auxiliary mixture 35 passages in parallel relation in said casing, each of said passages being in communication with said air inlet and said mixture outlet, a Venturi tube in each of said passages, a fuel jet operatively associated with each of said Venturi tubes, a control valve in said auxiliary mixture passage, a housing secured to said casing, a pressure-responsive diaphragm in said housing and operatively connected to said control valve, a conduit between said housing and said casing that places 45 one side of said pressure-responsive diaphragm in direct communication with said mixture outlet downstream of said manually operable throttle valve, and resilient means to bias said pressure-responsive diaphragm to valve-opening position, said resilient means and said diaphragm normally tending to maintain said control valve in open position but being operable by predetermined engine suction to close said control valve.

5. In a carburetor of the character described, 55 a casing providing a fuel mixture outlet and an air inlet, said outlet being adapted for connection to an intake passage of an internal combustion engine, a manually operable throttle valve in said mixture outlet, primary and auxiliary mixture passages in parallel relation in said casing, each of said passages being in communication with said air inlet and said mixture outlet, a Venturi tube in each of said mixture passages, a fuel jet operatively associated with each of said Venturi tubes, a control valve in said auxiliary mixture passage, a movable wall operatively connected to said control valve, adjustable spring means operative to bias said movable wall into valve-opening position, and conduit means 60 connected to said mixture outlet to place one side of said movable wall in direct communication with said mixture outlet downstream of said manually operable valve to overcome said bias and close said control valve by predetermined engine suction.

6. In a carburetor of the character described, a casing, an air-fuel mixture outlet for said casing that is adapted for connection to an intake passage of an internal combustion engine, a manually operable throttle valve that is in said mixture outlet and is operable to control the flow of air-fuel mixtures through said mixture outlet, primary and auxiliary mixture passages that are spaced apart and are spaced from said mixture outlet, a Venturi tube in each of said mixture passages, a fuel jet operatively associated with each of said Venturi tubes, the fuel jet and Venturi tube in said primary mixture passage being adapted to provide an air and fuel mixture that can pass to the said mixture outlet of said casing, said fuel jet and Venturi tube of said auxiliary mixture passage being adapted to provide an air and fuel mixture that also can pass to the said mixture outlet of said casing, a control valve in said auxiliary mixture passage that is openable to permit the air and fuel mixture of said auxiliary mixture passage to pass to the said mixture outlet of said casing and is closable to keep the air and fuel mixture of said auxiliary mixture passage from passing to the said mixture outlet of said casing, means normally tending to open said control valve, and a movable wall sub-

jectected on one side to the pressure in said mixture outlet downstream of said manually operable throttle valve to close said control valve by predetermined engine suction, whereby the flow of air and fuel from said primary mixture passage through the said mixture outlet of said casing is manually controlled while the flow of air and fuel from said auxiliary mixture passage through the said mixture outlet of said casing is pressure controlled as well as manually controlled.
